UNITED STATES PATENT OFFICE.

MAX COLUMBO, OF BAYONNE, NEW JERSEY.

DESIGN FOR A GAME-BOARD.

SPECIFICATION forming part of Design No. 25,534, dated May 19, 1896.

Application filed August 31, 1895. Serial No. 561,162. Term of patent 3*1* years.

To all whom it may concern:

Be it known that I, MAX COLUMBO, a citizen of the United States, residing at Bayonne, county of Hudson, State of New Jersey, have 5 invented and produced a new and original Design for Game-Boards, of which the following is a specification, reference being had to the accompanying drawings, in which—

Figure 1 represents a plan view of my game-board, and Fig. 2 a cross-section on line *x x* of Fig. 1.

The leading feature of my design consists of the plane surface of the block, as A, which is square, and a similar square plane bottom 15 space inclosed by the plates or flanges B, together with the transverse flanges C, the horizontal flanges D, the curved segmental flanges E, by means of which the space between the flanges B is divided into four main compartments F, G, H, and K. In one end of the compartment G is an open circular flange M, within which is an angular flange *m*, forming a small square compartment, one side of which is open, and within the other end of the compartment G is placed two segmental flanges N, by means of which a circular space is formed, open at both sides, within which is placed an angular flange forming a square compartment open at one side. The compartment K on the opposite side is provided with similar circular flanges M and N, and small square compartments *m* and *n* within

the spaces thus formed, and the main portion of the compartment F is provided with a square compartment heretofore described, 35 and within the extension of the compartment F and the further end thereof is placed a series of concentric flanges P, open at opposite points, whereby annular chambers are formed, said circular flanges being united by 40 radial flanges R, and between the said circular flanges P and the square compartment O are irregular flanges S, which divide the extension of the compartment F and are separated by spaces S'. It will be seen that the 45 main or principal lines or flanges of my design are straight and that the circular flanges are so arranged in the main compartment as to produce a pleasing effect to the eye, and the entire device is symmetrical and artistic 50 in construction.

Having fully described my improved original design, I claim and desire to secure by Letters Patent—

The design for a game-board, substantially 55 as herein shown and described.

In testimony that I claim the foregoing as my invention I have signed my name, in presence of the subscribing witnesses, this 31st day of July, 1895.

MAX COLUMBO.
